DISPENSER FOR CONCENTRATES AND THE LIKE

Carl C. Bauerlein, Mukwonago, Wis., assignor to The Dole Valve Company, Chicago, Ill., a corporation of Illinois

Application May 31, 1951, Serial No. 229,121

4 Claims. (Cl. 222—57)

This invention relates to dispensers for diluting and dispensing fluids or concentrates, such as concentrated juices, malts, liquors, colas, flavors and the like.

It is an object of my invention to provide a novel and improved form of mixing and dispensing valve having no moving parts and operable to dispense a fluid of one consistency by the flow of a diluting fluid through the valve under pressure.

Another object of my invention is to provide an efficient form of dispensing valve of a simplified and novel construction and arrangement wherein the concentrate or fluid is dispensed and mixed with water by the aspirating action of the water under pressure passing through a throat of a Venturi.

A further object of my invention is to provide a novel and simple form of a dispensing valve for concentrates or fluids wherein the control of the flow of the concentrate or fluid is attained by the flow of diluting water through the valve as the water passes through a vacuum chamber on the downstream side of the throat of a Venturi.

A still further object of my invention is to provide a new and improved form of mixing and dispensing valve utilizing the flow of diluting water to draw a concentrate or fluid from its container and utilizing a flexible wafer to prevent leakage of the concentrate or fluid from the container when the flow of diluting water through the valve is cut off.

A still further object of my invention is to provide a new and improved form of dispensing valve for high specific gravity liquids having a resilient wafer type check valve at the top of the valve body to prevent leakage of the liquid through the valve body by the head on the liquid and utilizing a vacuum chamber on the downstream side of the throat of a Venturi to aspirate the liquid through the valve.

Another and more detailed object of my invention is to provide an efficient form of dispensing and mixing valve for concentrates or fluids made from a transparent insulating material with all the passageways of the valve readily exposed to view and controlling the flow of the concentrate or fluid for mixture with water, entirely by the flow of the mixing and diluting water through the valve.

These and other objects of my invention will appear from time to time as the following specification proceeds and with reference to the accompanying drawings wherein:

Figure 1 is a fragmentary vertical sectional view taken through a dispenser constructed in accordance with my invention;

Figure 2 is a transverse sectional view taken through the dispensing and mixing valve;

Figure 3 is a top plan view of the mixing and dispensing valve;

Figure 4 is a horizontal sectional view taken through the mixing and dispensing valve, showing the Venturi and water passageway therein; and

2

Figure 5 is an enlarged sectional view taken along line V—V of Figure 3.

In Figure 1 of the drawings, I have shown a portion of a dispenser for diluting and dispensing various types of concentrates or fluids, such as concentrated vegetable juices and fruit juices, malts, liquors, colas, flavors and the like, and particularly adapted to dilute concentrates to the normal consistency of the juice of the fresh natural fruit and delivering a cool uniformly mixed juice for drinking purposes. The dispenser may include a casing 10 having a container or tank 11 for the concentrate or fluid, mounted therein adjacent the upper portion thereof and open at the top thereof. The tank 11 may be of a generally cylindrical form closed by a cover 12 and having a sloping bottom 13, gradually sloping to an opening 14 for a diluting and mixing valve 15.

As herein shown, the opening 14 is formed by a depending collar 16 forming an open-ended valve chamber and depending from the bottom of the tank. The depending collar 16 has an inwardly turned frusto-conical lower end portion 17 engaging the bottom of the valve 15 and holding it in place (Figure 2).

The tank 11 may be cooled by a refrigerating coil 19 and may be made from a corrosion-resistant material, such as stainless steel, which besides resisting corrosion of highly acid fruit juices, also acts as a conductor of cold, to maintain the juice cool, when the refrigerating unit is shut off. The tank 11 is formed to be free from all shoulders or recesses where bacteria may breed and the temperature of the concentrate is maintained sufficiently low to prevent the breeding of bacteria therein by the refrigerating coil 19, encircling said tank.

The casing 10 may also have a compressor, motor and condenser (not shown) for a refrigerating unit, which may be contained therein and may be connected to the refrigerating coil 19, to maintain the juice concentrate at the proper temperature, a desirable temperature being in the neighborhood of 22° F., although the concentrate may be maintained at higher or lower temperatures as long as it will flow relatively freely and is sufficiently cold to prevent the breeding of bacteria. It should here be understood that the freezing temperature of the concentrate is much lower than that of water, the freezing temperature of many concentrated fruit juices being as low as 18° F.

A supply pipe 20 for diluting water may enter the casing 10 through a wall thereof (not shown) and may extend through said casing to a position adjacent the top of the cooling coil 19. The pipe 20 may then be coiled around the outside of said coil, in spaced relation with respect thereto, as indicated by reference character 21. The supply pipe 20 is shown as being connected at its delivery end with a constant volume solenoid operated delivery valve 23. The valve 23 may be a solenoid controlled fluid pressure operated valve of a well known form of diaphragm type, and is not herein shown or described in detail except insofar as to show a fitting 24 threaded within the discharge outlet of the valve, and having an annular flow control member 25 contained therein. The flow control member 25 is seated in an annular recessed portion 26 of the fitting 24. Various flow control members may be substituted for the member 25 to control the flow of water through the valve, so that the valve may deliver the required volume of diluting water at the desired pressure. The flow control member 25 is shown as being a resilient flow control washer, similar to that shown and described in Patent No. 2,389,134, which issued to Clyde A. Brown on November 20, 1945, and is no part of my present invention, so need not herein be shown or described in detail.

A coil 29 for a solenoid encircles an armature (not shown) of the valve and is energized upon the pressing

of a push button 30 on the front face of the dispenser to open the valve to supply water at the desired pressure for aspirating and scavenging the concentrate from the tank 11 and mixing therewith. A pipe 31 leads from the fitting 24 and is connected at its discharge end to a pipe 33 extending outwardly from the collar 16 and communicating with the inside of said collar. A coupling 34 is provided to secure the end of the pipe 31 to the pipe 33.

The mixing and dispensing valve 15 is herein shown as comprising a valve body 36 of a generally cylindrical form. The valve body 36 may fit within the collar 16 and be retained therein by the frusto-conical lower end portion 17 thereof, abutted by a corresponding lower face of said valve body. The valve body 36 is preferably transparent and may be molded or formed from one of the well known thermoplastic materials, or from glass. One such thermoplastic material may be "Lucite," which not only exposes the passageways in the valve to view, but also acts as an insulator and inhibits freezing of the water.

The valve body 36 is shown as having an annular passageway 39 extending therearound and opening to the periphery thereof and communicating with the pipe 33, for conducting water under pressure into and through the valve body. Sealing rings 40, 40 may be provided on opposite sides of the annular passageway 39, to retain water in said passageway and to prevent the leakage of water along the side walls of the valve body 36. Said sealing rings may be of any well known form of flexible sealing ring, made from rubber or an elastomer, as long as the rings and recesses in the wall of the valve body for the rings are so constructed that they may readily be cleaned and will not harbor the breeding of bacteria.

The valve body 36 is shown as having its top face recessed slightly below the bottom of the tank 11 and as having a concentrate chamber 41 recessed therein and opening to the top thereof. A cage 42 of a check valve 43 is shown as being recessed in the top of said chamber and suitably sealed to the wall thereof. The cage 42 has a plurality of flow apertures 44, 44 opening through the bottom thereof. Flow apertures 45, 45 are provided in the side wall thereof, to assure complete scavenging of the concentrated juice from the bottom of the tank 11.

The check valve is herein shown as being a flexible wafer 46 which may be made from rubber or an elastomer. The wafer 46 has a plurality of nibs 47, 47 extending upwardly therefrom through certain of the apertures in the bottom of the cage 42 and retaining said wafer to the bottom of said cage. As herein shown, the nibs 47, 47 are diametrically aligned and allow the wafer to flex downwardly on opposite sides of the centers thereof, to allow the flow of concentrate through the apertures 44, 44 and 45, 45. The bottom of the cage 42, abutting the wafer 46 is convex and said wafer has sufficient flexibility to normally engage the convex bottom of the cage 42 and prevent the leaking of concentrate therethrough by gravity, but to flex upon the reduction in pressure in the chamber 41 and allow the concentrate to pass through the apertures 44, 44.

The concentrate chamber 41 communicates with a generally cylindrical outlet 49 at the bottom thereof having a generally frusto-conical bottom portion 50 terminating in a knife-edge orifice 51. The knife-edge orifice 51 communicates with a vacuum chamber 53 on the downstream side of a throat 54 of a Venturi 55.

The vacuum chamber 53 on the downstream side of the throat 54 of the Venturi is of a larger diameter than the diameter of the throat of the Venturi to assure the free flow of concentrate into the vacuum chamber by the increased velocity of the water flowing therethrough as it leaves the throat of the Venturi. The knife-edge orifice 51 is provided to reduce the surface tension of the relatively heavy viscous concentrate and to accommodate the concentrate to freely flow into the vacuum

5

chamber 53 regardless of changes in viscosity thereof due to the proportioning of different forms of concentrates or to variations in the viscosity of the concentrate due to temperature changes.

A knife edge orifice is herein defined as being an orifice having a sharp inlet edge and having a wall of negligible axial length.

A passageway 56 leads from the annular passageway 39 through the valve body 36 and terminates into the base of a truncated cone-like passageway, forming the upstream side of the Venturi 55. An inverted truncated cone-like passageway leads from the vacuum chamber 53 and communicates with a downwardly extending inclined passageway 60, opening to the bottom of the valve body 36. As herein shown, a spout or nozzle 61 is secured to and depends from a depending portion 63 of the valve body 36, to direct the mixed and diluted concentrate for discharge into a drinking glass or other suitable container.

When the tank 11 has concentrate therein, and water from the valve 23 enters the valve body 36 at a predetermined generally constant pressure governed by the valve 23, through the annular passageway 39, the velocity of the water flowing through the throat 54 of the Venturi 55 will increase with a resultant drop in pressure at the downstream side of said throat, and create a vacuum in the vacuum chamber 53. This will draw the wafer 46 downwardly and open the check valve 43. The vacuum in the vacuum chamber 53 will thus aspirate the concentrate from the tank 11, mixing it with the water and discharging it through the spout 61, diluted to the consistency of the juice of the fresh fruit.

The flow of water from the water valve 23 may be regulated by the flow control member 25 to mix 4½ ounces of water with 1½ ounces of concentrate and deliver six ounces of diluted juice in six seconds. This may be attained with a delivery pressure of the water of around 10 pounds per square inch as it leaves the flow control washer 25. Water entering the passageway 56 under a pressure of around 12 pounds per square inch will create a vacuum in the vacuum chamber 53 of substantially 17 inches of mercury, which is sufficient to scavenge the tank 11 dry, when desired. It should, of course, be understood that by varying the passages, vacuum chamber, etc., that the same results may be attained with higher or lower pressures.

It has also been found that with sufficient vacuum in the vacuum chamber 53, the head pressure of the concentrate in the tank will in no way affect the flow of the concentrate from the tank, and that the flow of concentrate will be substantially uniform from the top to the bottom of the tank as the head decreases.

It has also been found that variations in incoming pressure of the water have very little effect on a variation of the mixture of the concentrate and that with changes in incoming pressure of around 25%, the variation in the Brix reading of the diluted concentrate is slight and is far better than the allowable requirements.

It has further been found that, although the apertures 44, 44 in the cage 42 are relatively small, with the above-mentioned vacuum in the vacuum chamber 53, or even with water pressure as low as 8 pounds per square inch, and a vacuum of 15 inches of mercury, fruit sacks will be extruded through these apertures past the check valve 43, and mixed with the flowing water without clogging the check or mixing valves. Satisfactory results may also be attained with lower pressures by varying the size of the passageways and particularly the vacuum chamber 53.

It may also be noted that if desired the valve may be cleaned without removing from the tank 11 by filling the tank with a detergent and water and aspirating the detergent through the valve and scavenging it from the tank 11 by opening the water valve 23.

It should also be noted that the valve body 36 is made from a transparent material such as "Lucite" or glass

which, besides being transparent and rendering all of the passageways open to view, to permit ready cleaning thereof, also acts as an insulator and inhibits freezing of the water or concentrate in the passageways therein. It should be understood, however, that while the valve body is shown and preferably described as being transparent and made from plastic or glass, it need not be transparent and may be made from other materials as well.

It will be understood that modifications and variations may be effected without departing from the spirit and scope of the novel concepts of the present invention.

I claim as my invention:

1. In a device for proportioning a liquid of relatively heavy viscosity with a liquid of relatively light viscosity and dispensing the proportioned liquids as a liquid mixture of predetermined proportions, a body member, a first inlet passageway in said body converging in a downstream direction and having a restricted throat, an outlet passageway extending in the same direction as said first inlet passageway and joining said throat, said outlet passageway having a larger cross-sectional area at said junction than the cross-sectional area of said throat, a second inlet passageway in said body member communicating with said portion of said outlet passageway of larger cross-sectional area than said throat, adjacent the junction of said outlet passageway to said throat, and said second inlet passageway having a portion of relatively large cross-sectional area and having an orifice in communication with said outlet passageway through the wall thereof of relatively small cross-sectional area, the portion of said inlet passageway defining said orifice being of a substantially shorter axial length than any radial measurement of said orifice.

2. In a device for proportioning a liquid of relatively heavy viscosity with a liquid of relatively light viscosity and dispensing the proportioned liquids as a liquid mixture of predetermined proportions, a body member, a first inlet passageway in said body member converging in a downstream direction and having a restricted throat, an outlet passageway extending in the same direction as said first inlet passageway and joining said throat, said outlet passageway having a larger cross-sectional area at the junction of said outlet passageway with said throat than the cross-sectional area of said throat, a source of liquid under pressure having communication with said first inlet passageway, a second inlet passageway in said body member communicating with said portion of said outlet passageway through a wall thereof, adjacent the junction of said outlet passageway with said throat, a source of liquid of relatively heavy viscosity in communication with said second inlet passageway, and said second inlet passageway having a portion of relatively large cross-sectional area converging toward its downstream end and having an orifice at its downstream end of relatively smaller cross-sectional area than said portion of relatively large cross-sectional area, the portion of said second inlet passageway defining said orifice being of a shorter axial length than one-half of any radial measurement of said orifice.

3. In a device for proportioning a liquid of relatively heavy viscosity with a liquid of relatively light viscosity and dispensing the proportioned liquid as a liquid mixture of predetermined proportions, a body member, a

first inlet passageway leading into said body member and having a portion converging in a downstream direction into a restricted throat, an outlet passageway extending in the same direction as said inlet passageway and joining said throat, said outlet passageway having a portion of larger cross-sectional area at its junction with said throat than the cross-sectional area of said throat, a second inlet passageway in said body member communicating with said outlet passageway through a wall thereof adjacent the junction of said outlet passageway with said throat, a source of liquid of heavy viscosity in communication with said second inlet passageway, said second inlet passageway having a portion of relatively large cross-sectional area converging toward its downstream end into a knife-edge orifice, a source of supply of liquid of light viscosity under pressure in communication with said first inlet, and uniform rate of flow control means providing a uniform rate of flow of liquid of light viscosity into said first inlet and providing a substantially uniform vacuum and flow of liquid of heavy viscosity regardless of variations in head of the liquid of heavy viscosity.

4. In a device for proportioning a liquid of relatively heavy viscosity with a liquid of relatively light viscosity and dispensing the proportioned liquid as a liquid mixture of predetermined proportions, a body member, a first inlet passageway leading into said body member converging in a downstream direction to a restricted throat, a vacuum chamber on the downstream side of said throat, an outlet passageway leading from said vacuum chamber, said vacuum chamber having a larger cross-sectional area than the cross-sectional area of said throat, a source of proportioning liquid under pressure in communication with said inlet passageway and having a uniform rate of flow control device on the upstream side of said inlet passageway assuring a uniform rate of flow of proportioning liquid regardless of variations in pressure of the liquid at the source, a second inlet passageway in said body having communication with said vacuum chamber through a wall thereof, a source of supply of liquid of relatively heavy viscosity having communication with said second inlet passageway, said second inlet passageway having an inlet portion of relatively large cross-sectional area and having a converging wall defining at its downstream end a knife-edge orifice of relatively small cross-sectional area.
